PHENOLPHTHALEIN COMPOUNDS AND
METHODS OF PRODUCING THE SAMEStanley E. Cairncross, Winchester, Mass., assign-
or to Bristol-Myers Company, New York, N. Y.,
a corporation of DelawareNo Drawing. Application August 19, 1939,
Serial No. 290,943

38 Claims. (CL 260—210)

This invention relates to glycosides of phenol-phthalein, and to a method of making the same.

Phenolphthalein is used extensively as a laxative. However, such use is limited because it is quite insoluble in water, having a solubility of only 0.02 part in 100 parts of water at 20° C. Since the average dose of phenolphthalein is about 0.06 to 0.18 gram, it would therefore require about 300 c. c. to 900 c. c. of water to effect solution of a single dose. Accordingly, it would be impracticable to prepare and distribute an aqueous solution of phenolphthalein as a commercial product because it would be too bulky.

Soluble compounds of phenolphthalein, such as the sodium salt, have been made. But such compounds are exceedingly bitter, strongly colored and unstable in solution, and for these and other reasons their use for medicinal purposes is restricted or undesirable.

It is therefore an object of this invention to prepare compounds of phenolphthalein which are much more soluble in water than phenolphthalein and which are more easily administered and are presented to the fluids of the human system in a different form from the customary phenolphthalein, and in which, moreover, the phenolphthalein component is at the same time readily available to perform its laxative or other therapeutic functions.

Another object is to provide some compounds of phenolphthalein which are preferably essentially colorless, and either substantially tasteless or at least palatable.

A further object is to provide a class of compounds or derivatives of phenolphthalein which are new compositions of matter, per se, and which may be useful, if not as medicinal agents then for such other purposes as their specific characteristics may render them suitable.

Another object is to provide a method of making such derivatives or compounds.

Other objects will appear from the following disclosure.

The class of compounds or derivatives to which this invention relates are the glycosides of phenolphthalein. These derivatives are compounds which are generically constituted by the union of phenolphthalein and a sugar. The terms "glycosides" and "glucosides" have heretofore been used more or less as equivalents. But properly the former is the broader term and includes the latter group of compounds—and this is the more current usage at the present time.

Generically, a glycoside is a derivative of a sugar cyclic hemi-acetal, formed by the etherifi-

cation of the hemi-acetal hydroxyl group with a hydroxy-carbon compound, and has the property of furnishing a sugar and one or more other products when hydrolyzed by acid.

In the present description and in the following claims, phenolphthalein "glycosides" are to be considered as the class of products resulting from the union of phenolphthalein and a sugar by etherification, to form a derivative of a sugar cyclic hemi-acetal, having the property of furnishing a sugar and free phenolphthalein when hydrolyzed by acid.

In the molecular structure of the glycosides obtained by the method of the present invention, one oxygen atom of the sugar radical bridges between the reducing carbon atom and a carbon atom of the chain of the sugar radical, while another oxygen bridges between the reducing carbon atom and one of the carbon atoms of phenolphthalein to effect, in all, a cyclic mixed acetal or glycoside structure. A typical illustration of this structure is given in the following formula, in which the sugar is a typical aldohexose such as glucose, and P represents a phenolphthalein radical:

Using a similar sugar, a typical diglycoside of phenolphthalein may therefore be represented as follows:

The internal structure, orientation, or arrangement (such as *d*- and *l*-, α and β , cis and trans, etc.) of the sugar component of the glycoside radical or radicals may vary in accordance with their inherent characteristics and yet be susceptible of entering into the above structure.

"Glucosides" are the class or group of "glycosides," as above defined, in which the sugar component is a glucose residue or radical.

The sugars capable of use in the present method and of constituting a component of the glycosides produced thereby include trioses, tetroses, pentoses, methyl pentoses, hexoses, and also the lower, reducing poly-saccharid sugars having two, three or four mono-saccharide components,

which are characteristically soluble in water and may be referred to, as a group, as the reducing oligo-saccharides. They may be of aldose or ketose structure and may present various isomeric arrangements of molecular structure and still be applicable for use, as hereinafter more fully described, so long as they are capable of existing in the form of a cyclic hemi-acetal and entering into and constituting the final product 10 as above defined.

The lower reducing poly-saccharide or reducing oligo-saccharide sugars are capable of forming glycosides and in fact are in themselves combinations of mono-saccharides in a form similar 15 to the structure of the glycosides and may be hydrolyzed as by acids into component mono-saccharides. For example, lactose is a galactosido-glucose, maltose a glucosido-glucose, and so on for other oligo-saccharides. Sugar-like 20 poly-saccharides or oligo-saccharides resemble mono-saccharides in many of their chemical properties as well as in having, in general, a high solubility in water and a sweet or pleasant taste. Non-sugar-like poly-saccharides, or higher poly- 25 saccharides such as the starches and cellulose, on the other hand, while being condensation products of mono-saccharides, are relatively insoluble in water and differ from them in chemical properties also. Because of these differences 30 they are not included in the present invention.

As is well known, the mono-saccharides are divided into two groups, the aldoses and the ketoses, according to whether they are respectively hydroxy-aldehydes or hydroxy-ketones. 35 They are also classified in accordance with the number of carbon atoms or in accordance with the number of oxygen atoms present in the molecule—e. g., as tetrose, pentoses, hexoses, etc. Furthermore, since all mono-saccharides 40 except the two simplest ones have one or more asymmetric carbon atoms, they must occur in stereoisomeric forms, thus making possible a large number of sugars differing only in atomic arrangements but similar in chemical structure 45 and reaction.

It has also been found that reducing saccharides can exist in two forms—which are called the α and β forms. This follows from the fact that the mono-saccharides do not exist wholly 50 in the open-chain form, but rather as, or in equilibrium with, the cyclic hemi-acetal form, viz:

55 and this cyclic form presents a new asymmetrical carbon atom, represented by the asterisk (*). For each open chain saccharide there may therefore be two isomeric cyclic forms which differ only in the arrangement of the groups around the carbon atom represented above by the asterisk. The α and β forms are distinct compounds, and differ in solubility, melting points of their derivatives, and optical properties. 60 Hence the glycosides may exist in either the α or the β form.

In the diglycosides of the present invention, the two saccharide radicals will ordinarily be identical. However, this invention is not so limited, and is intended to include diglycosides of 65 phenolphthalein wherein the two saccharide radicals are different. These saccharide radicals may thus differ as between mono- and oligo-saccharides, or between aldoses and ketoses, or 70 between pentoses and hexoses, or between *d* and *l*.

forms, or between alpha and beta forms, or between two or more combinations of these, for example.

A suitable procedure for preparing the new compositions of this invention may be summarized briefly as follows: The desired sugar is reacted with acetic anhydride to convert it into the corresponding polyacetate; this product is then reacted with hydrogen bromide to convert it into the corresponding acetobrom compound; 10 this in turn is reacted with phenolphthalein to produce the polyacetyl-glycoside of the phenolphthalein, which is then treated to split off the acetyl radicals and give the final phenolphthalein glycoside. 15

The same procedure is followed whichever sugar is used, hence the following detailed example, wherein the sugar is glucose, will be a sufficient illustration of the procedure, which may be carried out with any other suitable sugar of 20 the class above defined.

The procedure as outlined above may be considered as having four steps. Each of these steps will be described in detail, in the example to be described below. When the final product is to 25 be used for medicinal purposes, special care should of course be taken to use pure materials and inert apparatus. When the product is to be used for other than therapeutical purposes, however, the materials, apparatus and procedure may 30 be less rigorously controlled accordingly.

EXAMPLE I

Preparation of phenolphthalein di-beta-glucoside

Step 1.—Preparation of glucose pentacetate. 35 This step may be carried out in the following manner: Mix 700 grams anhydrous glucose and 250 to 350 grams anhydrous sodium acetate in a suitable flask, and add 3500 grams acetic anhydride. The flask is held in a water bath at about 35° C., and the contents stirred intermittently to prevent localization of heat while the reaction proceeds, which requires about an hour. The resulting mixture is then held at that temperature for about two hours, after which it is added 40 slowly over a period of about one-half hour to about ten times its volume of ice water, with vigorous stirring. The product precipitates in the form of white crystals, which are removed 45 from the liquid phase by filtration and dried carefully—first in the air for about 12 hours and then for 4 to 5 hours in a forced-draft oven at about 60° C. The yields from several runs ranged from 80 to 90% of the theoretical, based on the 50 original glucose: Average yield was 1300 grams, or 85% of theoretical, of the product, which is 55 glucose pentacetate.

Step 2.—Preparation of acetobromglucose.

Acetobromglucose (tetra acetyl glucosidyl bromide) may be prepared by the direct reaction in 60 glacial acetic acid of HBr and glucose pentacetate, prepared as described above and consisting principally of beta glucose pentacetate or prepared in some other manner, for example, with zinc chloride as a catalyst and consisting principally of alpha glucose pentacetate. This 65 method has been adopted in carrying out Step 2 of the present procedure, which is performed as follows: Mix 1000 grams of the glucose pentacetate obtained as in Step 1 with 2000 grams of an 18 to 20% solution of HBr in glacial acetic acid, and agitate until solution is complete; let this 70 solution stand at room temperature for about 2 hours. Then add a selective solvent for the 75

acetobromglucose—e. g., 2 liters of chloroform—decant the mixture onto crushed ice, separate from the resulting two-phase mixture the chloroform solution of acetobromglucose and wash it, first with ice-water, then with a suitable neutralizing agent for any traces of acetic acid and HBr—e. g., an ice-cold sodium bicarbonate solution—and finally with ice-water again. The resulting neutral chloroform solution is dried to remove any water present, as by mixing with anhydrous Na_2SO_4 , and separating from the Na_2SO_4 as soon as the chloroform solution is clear. The yields of the crystallized product from several runs ranged from 60 to 80% of the theoretical based on the glucose pentacetate.

If desired, the acetobromglucose may be separated from the chloroform solution in known manner by partially evaporating the chloroform solution at 50° C. under reduced pressure to form a thick syrup, washing with a little dry ether, and adding 15 to 20 volumes of petroleum ether to precipitate the acetobromglucose as a thick syrup which on cooling, with stirring, crystallizes and is then filtered off. It may be further purified by redissolving in dry ether and then evaporating the ether. Other procedures may be used for recovering the acetobromglucose.

Step 3(A).—Preparation of phenolphthalein di-beta-tetracetyl - glucoside. Acetobromglucose prepared in accordance with Step 2 is reacted with phenolphthalein in the presence of substances which are effective to remove the HBr and preferably water which are produced by the reaction. It is important that this removal take place during the reaction, as the HBr tends to reverse the reaction and/or to cause undesirable side reactions, while the water tends to decompose the acetobromglucose. The acetobromglucose used in this step may be either the dry crystalline solid, or the chloroform solution, the preparation of each of which is described in Step 2. Alternatively, the acetobromglucose may be prepared in other ways.

One method of carrying out Step 3 is as follows:

Ingredients:

Acetobromglucose	grams	411	(1 mol)
Phenolphthalein	do	213	(0.67 mol)
Quinoline	c. c.	250	
Silver oxide	grams	250	
Dioxane	c. c.	200	

It is desirable to have all the ingredients pure and water- and alcohol-free.

The phenolphthalein and quinoline are mixed; the dioxane and acetobromglucose are added and the mixture stirred. The acetobromglucose may be in chloroform solution when added, or it may be dry, in which event chloroform should be added to effect solution. The silver oxide is then added preferably in several successive steps, while stirring and keeping the mixture at a temperature of not over 45° C. After heat evolution ceases, stirring is continued for one to two hours, keeping the mixture at about 40° C. Then the solid residues (chiefly silver bromide and any excess silver oxide) are removed by filtration, and washed with chloroform until substantially colorless, the washings being combined with the filtrate. The filtrate, after treating with zinc dust, is then concentrated as nearly dry as possible, under reduced pressure, and preferably at a temperature not over 60° C., and the residue taken up in 750 c. c. of hot 95% ethyl alcohol and then refrigerated, whereupon crystals separate and are filtered off, with

thorough washing with cold 95% ethyl alcohol. The resulting filter cake of crude phenolphthalein di-beta-tetracetyl-glucoside is dissolved in 1.5 times its weight of glacial acetic acid with warming and recrystallized by addition of 14 parts of 95% ethyl alcohol and cooling (e. g., to about 5 to 10° C.). The resulting product is phenolphthalein di-beta-tetracetyl-glucoside. The yields from several typical runs ranged between 30% and 50% of theoretical, based on the acetobrom- 10 glucose.

Step 3(B).—The foregoing procedure may be modified to advantage in several ways, some of which are indicated below. Thus, starting with the same amount of acetobromglucose, the amount of phenolphthalein may be between 160 15 grams (0.5 mol) and 640 grams (2 mols), the quinoline and dioxane may be omitted, and a suitable drying agent may be added such as "Drierite," which is a trade name for a specially prepared form of anhydrous calcium sulfate in the form of porous pellets which are capable of taking up one-half mol of water (to form $2\text{CaSO}_4 \cdot \text{H}_2\text{O}$) while still retaining their shape. This is preferable to the use of the ordinary 25 semihydrate (plaster-of-Paris), as the latter on addition of water sets to a solid cake which is difficult to manipulate or separate.

With these modifications, the procedure is as follows, starting with the same amount of acetobromglucose as above. The phenolphthalein, the silver oxide, and the "Drierite" (about 400 to 500 grams) are mixed with part of the chloroform and stirred for an hour or so to complete drying. The acetobromglucose with the balance of the chloroform (total about 2000–3000 c.c. of chloroform from both sources) are added slowly enough to control heat evolution due to the reaction.

After the reaction is completed, as evidenced by absence of further evolution of heat and absence of bromide ion in the solution, the Ag Br and any excess Ag_2O and phenolphthalein are removed and subsequent steps followed as in the quinoline procedure just described. The purification is, however, somewhat simpler than when using quinoline, as the solutions obtained are much easier to concentrate to dryness. Furthermore, less effort is required to obtain a pure product; the solutions are light in color and fairly clear as compared with those using quinoline, which are dark or even almost black.

The choice of solvents used depends on results and course of reaction desired. E.g., chloroform dissolves acetobromglucose but not phenolphthalein. Phenolphthalein is soluble in dioxane, however. Hence the solvents may be chosen so as to dissolve one or both principal reagents, as well as with respect to the product, which may or may not be precipitated accordingly.

The phenolphthalein di-beta-tetracetyl- glucoside thus prepared is a new compound, and has the molecular formula $\text{C}_{48}\text{H}_{50}\text{O}_{22}$, which may also be represented as $\text{C}_{20}\text{H}_{12}\text{O}_2[\text{OC}_6\text{H}_7\text{O}_5(\text{COCH}_3)_4]_2$ and hence has a calculated formula weight of 978. It is a white crystalline solid having a melting point of 225–226° C. It is easily soluble in the lower fatty acids such as formic and acetic acids, in the lower esters such as methyl acetate, in acetone, chloroform, nitrobenzene, and pyridine, 70 as well as in various other solvents. It is, however, insoluble or practically so in water and in carbon tetrachloride, and sparingly soluble in hot ethyl alcohol.

An analysis of a typical sample of the phe- 75

phenolphthalein di-beta-tetracetyl-glucoside gave the following results:

5		C	H
		Percent	Percent
Calculated.....		68.87	5.15
Found.....		58.74	5.18

10 *Step 4.*—Preparation of phenolphthalein di-beta-glucoside. The product of Step 3 is de-acetylated to give the final product. This may be done by following usual deacetylating procedure; thus, in the present instance, the phenolphthalein di-beta-tetracetyl-glucoside is refluxed for 1 to 2 hours with about twice its weight of substantially anhydrous methyl alcohol containing sodium methylate in an amount such that its sodium content is equal to about 0.1% of the 20 glucoside compound. The sodium methylate acts to catalyze the reaction, which is one of alcoholysis. The reaction is substantially complete when all the phenolphthalein di-beta-glucoside is in solution. Carbon dioxide is then passed into 25 the solution to decompose the sodium methylate, thus combining with the sodium to form sodium carbonate. This sodium carbonate, which is insoluble in the reaction mixture, is largely removed by filtration—with the use of activated 30 carbon as a filter aid if desired. The filtrate is evaporated to dryness to remove the methyl acetate produced and the excess methyl alcohol, and the dry product is phenolphthalein di-beta-glucoside. The yields are practically theoretical. 35 The methyl alcohol is used in excess because it serves as a solvent for the product as well as to react with the starting material. Other anhydrous low-boiling alcohols, such as ethyl, in which the final product is soluble, may be used in place 40 of methyl alcohol, although methyl alcohol appears to work most satisfactorily. De-acetylation may also be effected with other reagents such as ammonia or barium hydroxide.

45 Phenolphthalein di-beta-glucoside is a new compound, and has the molecular formula $C_{32}H_{34}O_{14}$, which may also be represented as $C_{20}H_{12}O_2(OC_6H_{11}O_5)_2$, and hence has a calculated formula weight of 642. It is very soluble in water and in the lower alcohols such as methyl and 50 ethyl alcohols, and also in pyridine. It is insoluble in chloroform, acetone, and petroleum ether, and only very slightly soluble in hot nitrobenzene. Its exact solubility in water is not readily determined, as it dissolves therein in an amount at 55 least sufficient to form a syrupy solution. It is a white powdery solid. The optical rotation of several representative samples in water ranged between -48.9° and -50.4° , averaging

$$[\alpha]_D^{20} = -49.7^\circ$$

60 It does not reduce Fehling's solution.

Clinical and toxicity tests

65 Extensive toxicity tests on animals have been made using the phenolphthalein di-beta-glucoside so prepared, and this product has been found to be non-toxic when taken either orally or intravenously except when taken in amounts very greatly in excess of the proper dosage for ordinary laxative effects.

70 Clinical tests have been made in approved manner in several age groups ranging from 6 years to 86 years of age, in comparison with ordinary phenolphthalein. These tests showed that 75 the phenolphthalein di-beta-glucoside was at

least as effective, weight for weight, as phenolphthalein, and in a number of cases was at least twice as effective. No unfavorable reactions to either compound were observed.

General

75 For economical operation it is practicable to recover reagents and by-products from the several steps in the process. Solvents such as chloroform from Steps 2 and 3 and methyl alcohol from Step 4 may be readily recovered, in suitable condition for reuse, as well as washing agents such as the ether used in Step 2 and the alcohol in Step 3. By-products such as acetic acid from Step 1 may also be recovered. In Step 3, it is 10 particularly desirable to recover the silver compounds, and generally any excess phenolphthalein; these can easily be treated to render them suitable for reuse.

EXAMPLE II

Preparation of phenolphthalein di-beta-galactoside

20 Phenolphthalein di-beta-galactoside is prepared by the procedure as described in Example 25 I, except that in Step 1 the glucose is replaced by an equal weight of galactose.

25 The final product is a white crystalline solid having the same molecular formula and molecular weight as those already given for phenolphthalein di-beta-glucoside. It has a melting point of 162–164° C. It is very soluble in methyl alcohol, 30 fairly soluble in hot or cold acetone or pyridine, hot nitrobenzene and hot ethyl alcohol, but less soluble in cold ethyl alcohol. It is insoluble in chloroform or petroleum ether. It is only slightly soluble in water, to the extent of about 1% in hot water and less in cold water. It does not reduce Fehling's solution. Rotation of a representative sample was 35

$$[\alpha]_D^{20} = -32.4^\circ$$

40 in absolute methyl alcohol.

45 The intermediate product, phenolphthalein di-beta-tetracetyl-galactoside, is a white powdery 45 solid having the same molecular formula and formula weight as those already given for phenolphthalein di-beta-tetracetyl-glucoside. It is readily soluble in chloroform, fairly soluble in methyl alcohol, and practically insoluble in water. It is 50 soluble in pyridine, acetone, and in ethyl acetate. The optical rotation of a representative sample was 55

$$[\alpha]_D^{20} = +21.0^\circ$$

60 Preliminary tests have indicated that the phenolphthalein di-beta-galactoside is an even more effective laxative agent than the corresponding glucoside, and that it is comparable with the glucoside and with phenolphthalein in its non-toxic properties.

ADDITIONAL MODIFICATIONS OF PROCEDURE

65 Various modifications have already been given in the several steps for obtaining the products of the present invention. Other modifications are 65 possible, of which the following will be mentioned:

70 Instead of the bromine compounds, the corresponding chlorine compounds may be made and used. Thus, acetochloroglucose may be the product of Step 2 in Example I. As a rule, however, the bromine compounds are more active.

75 Also, the acetobrom (or chlor) glucose may be made by the acetyl halide synthesis, wherein acetyl bromide or acetyl chloride is reacted di-

rectly upon the glucose or other sugar in the presence of HBr or HCl or a small amount of water. From the standpoint of yield, costs, and operation, the procedure previously described herein is, however, generally preferable.

Again, the acetate radicals may be replaced by other acyl radicals, particularly those of the lower fatty acids, e. g., formic, propionic, etc., with corresponding change in products. Thus, 10 the products from Step 3 would be phenolphthalein di-polyformyl (or poly-propionyl, or other polyacyl) glycosides. From the standpoint of ease of operation, and cost, these esters with the lower fatty acids, especially acetic, are preferred 15 for use in the present invention. However, the esters may be made with other organic acids, e. g., with higher fatty acids, or with aromatic acids, thus providing acylhalosaccharides as starting materials for Step 3 and giving as products of 20 Step 3 phenolphthalein di-polyacyl-glycosides, for example phenolphthalein dipolystearyl-glycosides, phenolphthalein di-poly-benzoyl-glycosides, etc.

Other hexose sugars than glucose and galactose 25 may be used in the same manner, such sugars including both keto- and aldo-hexoses. Similarly, pentoses and lower mono-saccharides may be employed, as well as the reducing oligo-saccharides hereinbefore referred to. 30 Hence the products of the present invention are more especially the phenolphthalein glycosides and the corresponding phenolphthalein di-glycosides. Ordinarily, in any given di-glycoside of either type, both saccharide radicals 35 will be identical, and in any given compound of the second (the polyacyl) type, all the acyl radicals will be identical. It would be possible, however, although hardly practical under any ordinary circumstances, to have different saccharide 40 radicals, or to have different acyl radicals, or both.

FORMULATION

While the di-glycosides of phenolphthalein are 45 not all equally soluble in water, they are as a rule sufficiently soluble to permit of being compounded into aqueous concentrates or elixirs of sufficient strength that one or two teaspoonsfuls of the concentrate or elixir contain enough of the phenolphthalein di-glycoside to be adequate for an 50 average normal dose as a laxative. This contrasts with about 300 c. c. of water necessary to take up an equally effective amount of phenolphthalein, as already pointed out.

Formulation of an elixir of a phenolphthalein di-glycoside may be carried out as follows: Boil together 450 grams of water, 380 grams of cane sugar, and 11 grams of phenolphthalein di-glucoside, stirring to promote solution. Then cool, 55 and filter if desirable. Mix the resulting solution with a second solution made of 100 c. c. of 95% ethyl alcohol, 25 c. c. of water, and sufficient flavoring, e. g., 10 c. c., and make the resulting solution up to one liter with water. Elixirs so prepared have shown no tendency to ferment, decompose, or otherwise change or lose their efficacy, unless appreciably on either the acid or alkaline side of neutrality. Such acidity or alkalinity would only be introduced by the flavoring, 60 or other ingredients of the elixir, and hence can be readily avoided in the formulation. The preferred pH range is between about 4.5 and 9.5. However, if the elixir is likely to be exposed to sunlight for any considerable length of time, the 65 range on the alkaline side should preferably be

reduced to about 8.5—i. e., with an overall pH range between about 4.5 and 8.5.

While a detailed description of the production of particular phenolphthalein di-polyacyl-glycosides and phenolphthalein di-glycosides, and of the use of the latter group of compounds as laxative agents, has been given, it should, of course, be understood that these compounds, being new compositions of matter, are not herein restricted to any single specific use but may be utilized for 10 various purposes; and furthermore, that the description herein is given by way of illustration, and that the scope of the invention is therefore to be considered as limited only by the scope of the appended claims.

I claim:

1. Method of preparing compounds of phenolphthalein, which comprises reacting phenolphthalein with an acyl-halo-saccharide, in the presence of a reagent to remove the halogen, to 20 form a phenolphthalein acyl glycoside.

2. A method according to claim 1 in which the acyl-halo-saccharide is a saccharide of the class consisting of bromo and chloro saccharide esters of the lower fatty acids.

3. A method according to claim 1 in which the acyl-halo-saccharide is an acetyl bromo saccharide.

4. Method of preparing compounds of phenolphthalein, which comprises reacting phenolphthalein with an acyl-halo-saccharide, in the presence of a solvent for at least one of the reacting ingredients and a reagent to remove the halogen in the form of halide which is inert toward the product, to form a phenolphthalein 30 acyl glycoside.

5. Method of preparing compounds of phenolphthalein, which comprises reacting phenolphthalein with an acyl-halo-saccharide, in the presence of a solvent, a dehydrating agent, and 40 a reagent to remove the halogen in the form of a halide which is inert toward the product, to form a phenolphthalein acyl glycoside.

6. Method of preparing compounds of phenolphthalein, which comprises reacting phenolphthalein with an acyl-halo-saccharide, in the presence of a solvent and a reagent to remove the halogen in the form of an insoluble halide, to 45 form a phenolphthalein acyl glycoside.

7. Method of preparing compounds of phenolphthalein, which comprises reacting phenolphthalein with an acyl-halo-mono-saccharide, in the presence of a solvent and a reagent to remove the halogen in the form of an inert halide, to 50 form a phenolphthalein acyl glycoside.

8. Method of preparing compounds of phenolphthalein, which comprises reacting phenolphthalein with an acyl-halo-poly-saccharide, in the presence of a solvent and a reagent to remove the halogen in the form of an inert halide, to 55 form a phenolphthalein acyl glycoside.

9. Method of preparing compounds of phenolphthalein, which comprises reacting phenolphthalein with an acyl-halo-saccharide, in the presence of a reagent to remove the halogen, to 60 form a phenolphthalein acyl di-glycoside.

10. Method of preparing compounds of phenolphthalein, which comprises reacting phenolphthalein with an acyl-halo-mono-saccharide, in the presence of a solvent for one of the reacting 70 ingredients and a reagent to remove the halogen as a halide which is inert to the product, to form a phenolphthalein acyl di-beta-glycoside.

11. Method of preparing compounds of phenolphthalein, which comprises reacting phenol-

- phthalein with an acyl-halo-saccharide, in the presence of a reagent to remove the halogen, to form a phenolphthalein acyl glycoside, and de-acylating the resulting phenolphthalein acyl glycoside to form a phenolphthalein glycoside.
12. A method according to claim 11 in which the acyl-halo-saccharide is a saccharide of the class consisting of bromo and chloro saccharide esters of the lower fatty acids.
- 10 13. A method according to claim 11 in which the acyl-halo-saccharide is an acetyl bromo saccharide.
14. A method according to claim 1 in which the acyl-halo-saccharide is a monohalo saccharide.
- 15 15. A method according to claim 1 in which the reagent to remove the halogen is silver oxide.
16. Method of preparing compounds of phenol-phthalein, which comprises reacting phenol-phthalein with an acyl-halo-saccharide, in the presence of a solvent for at least one of the reacting ingredients, and a reagent to remove the halogen in the form of a halide which is inert toward the product, to form a phenolphthalein acyl glycoside, and deacylating the resulting phenolphthalein acyl glycoside to form a phenolphthalein glycoside.
- 20 17. Method of preparing compounds of phenol-phthalein, which comprises reacting phenol-phthalein with an acyl-halo-saccharide, in the presence of a solvent, a dehydrating agent, and a reagent to remove the halogen in the form of an inert halide, to form a phenolphthalein acyl glycoside, and de-acylating the resulting phenolphthalein acyl glycoside to form a phenolphthalein glycoside.
- 25 18. Method of preparing compounds of phenol-phthalein, which comprises reacting phenol-phthalein with an acyl-halo-saccharide, in the presence of a solvent and a reagent to remove the halogen in the form of an insoluble halide, to form a phenolphthalein acyl glycoside, and de-acylating the resulting phenolphthalein acyl glycoside to form a phenolphthalein glycoside.
- 30 19. Method of preparing compounds of phenol-phthalein, which comprises reacting phenol-phthalein with an acyl-halo-mono-saccharide, in the presence of a solvent and a reagent to remove the halogen in the form of an inert halide, to form a phenolphthalein acyl glycoside, and de-acylating the resulting phenolphthalein acyl glycoside to form a phenolphthalein glycoside.
- 35 20. Method of preparing compounds of phenol-phthalein, which comprises reacting phenol-phthalein with an acyl-halo-poly-saccharide, in the presence of a solvent and a reagent to remove the halogen in the form of an inert halide, to form a phenolphthalein acyl glycoside, and de-acylating the resulting phenolphthalein acyl glycoside to form a phenolphthalein glycoside.
21. Method of preparing compounds of phenol-phthalein, which comprises reacting phenol-phthalein with an acyl-halo-saccharide, in the presence of a solvent for at least one of the reacting ingredients and a reagent to remove the halogen in the form of a halide which is inert toward the product, to form a phenolphthalein acyl-di-glycoside, and de-acylating the resulting phenolphthalein acyl di-glycoside to form a phenolphthalein di-glycoside.
- 25 22. As a new class of chemical compounds, the glycosides of phenolphthalein.
23. As a new class of chemical compounds the di-glycosides of phenolphthalein.
24. As a new class of chemical compounds, the acyl-glycosides of phenolphthalein.
- 25 25. As a new class of chemical compounds, the acyl-di-glycosides of phenolphthalein.
26. As a new class of chemical compounds the glucosides of phenolphthalein.
27. As a new class of chemical compounds the acyl glucosides of phenolphthalein.
28. As a new chemical compound the di-tetra-30 acetyl glucoside of phenolphthalein.
29. As a new chemical compound, di-beta glucoside of phenolphthalein.
- 30 30. As a new chemical compound, di-beta galactoside of phenolphthalein.
31. A laxative including a glycoside of phenolphthalein.
32. A laxative including a di-glucoside of phenolphthalein.
33. A laxative including a di-galactoside of 40 phenolphthalein.
34. A laxative elixir comprising a solution of a glycoside of phenolphthalein.
35. A laxative elixir comprising a solution of a di-glycoside of phenolphthalein.
36. A laxative elixir comprising a solution of a glucoside of phenolphthalein.
37. A laxative elixir comprising an aqueous solution of di-beta glucoside of phenolphthalein.
38. A laxative elixir comprising a solution of a 45 galactoside of phenolphthalein.
- 50 STANLEY E. CAIRNCROSS.
